Patented Oct. 25, 1921.

INVENTOR

R. J. Altgelt
By Seymour & Wright
Attorneys.

UNITED STATES PATENT OFFICE.

RUDOLPH J. ALTGELT, OF SOUTH BEND, INDIANA, ASSIGNOR TO OLIVER CHILLED
PLOW WORKS, OF SOUTH BEND, INDIANA.

PLOW.

1,394,524.

Specification of Letters Patent. Patented Oct. 25, 1921.

Application filed December 29, 1919. Serial No. 348,085.

To all whom it may concern:

Be it known that I, RUDOLPH J. ALTGELT, a citizen of the United States, and a resident of South Bend, in the county of St. Joseph and State of Indiana, have invented certain new and useful Improvements in Plows; and I do hereby declare the following to be a full, clear, and exact description of the invention, such as will enable others skilled in the art to which it appertains to make and use the same.

This invention relates to improvements in plows and more particularly to a gang plow structure in which the beams are held properly spaced apart by means of braces,—the object of my present invention being to provide a gang structure in which extensions of the braces between the beams shall be utilized to reinforce and in effect, constitute parts of the rear ends of the beams and the plow standards which depend from said beams and to which the plow bases are secured.

With this and other objects in view the invention consists in certain novel features of construction and combinations of parts as hereinafter set forth and pointed out in the claims.

In the accompanying drawings; Figure 1 is a plan view, and Fig. 2 a rear view of a plow structure embodying my invention.

In the drawings I have shown a gang plow embodying three units, but it is evident that a greater or less number of units may be employed.

1, 2, 2^a represent plow beams and the beams 1, 2 may be spaced apart at their forward end portions by means of a cross bar 3 having flanges or extensions 4 bolted to the respective beams, while the forward end 40 portion of the beam 2^a may be bolted to the beam 2.

The rear ends of the beams are curved downwardly and form standard members 5.

The rear ends of the beams and their standard members are spaced apart and connected by diagonal braces 6 6^a provided with extensions 7 7^a and 7^b secured to the beams and are curved downwardly to conform to and lie against the standard members 5.

50 The extensions 7, 7^a are bolted to the standard members of adjacent beams and are of sufficient length to reinforce said standard members and, in effect constitute supplementary parts of the plow standards. The

standard at the rear end of each beam thus 55 comprises two members bolted together, one of said members constituting an extension of a brace disposed between two beams and the other standard member being integral with the beam. 60

A plow base 8 is located at the lower end of each two-part standard and is securely bolted to both parts thereof as at 9, 10.

The right hand brace extension of brace 6 (Fig. 2) may be of sufficient length to extend below the lower end of the standard portion of this beam and secured to the plow base with three bolts, while the other extension of this brace may be shorter than the standard of the central beam and takes only 70 two of the bolts which secure this standard to the central plow base. The left hand extension 7^a of the brace 6^a may be of sufficient length to take two of the bolts which secure the standard portion of beam 2^a to the plow 75 base, but the extension 7^b of the brace 6^a is short and does not take any of the bolts which secure the central plow base to the central standard.

The gang frame, comprising the beams 1, 80 2, 2^a, is provided with bearings 11—12 for a crank axle 13 and the latter is provided with a spindle portion which enters the hub of a land wheel 14. A bearing sleeve 15 is secured to the axle 13 and provides a bearing 85 for a crank axle 16,—the latter having a spindle portion which enters the hub of a furrow wheel 17. Suitable means may be provided to cause the two axles to move together when the plow frame is raised, as 90 disclosed in application filed on the 17th day of October, 1919 by Lloyd W. Stickley, Serial No. 331,302 but as these features do not constitute part of my invention, further reference to the same herein, is unnecessary. 95

Having fully described my invention what I claim as new and desire to secure by Letters-Patent, is:—

1. A plow structure comprising a plurality of plow beams, plow standards integral 100 with the rear ends of said beams, a brace extending from one plow beam to another, said brace having integral extensions at its respective ends, said extensions lying directly against rear portions of two beams 105 and the plow standards and constituting supplemental members of the latter, plow bases, and transverse bolts projecting

through parts of said plow bases and through said standards and also through said supplemental standards members.

2. A plow structure comprising a plurality of plow beams, plow bases, plow standards at the rear ends of said beams, a brace extending from one beam to another, said brace provided at its ends with extensions which lie directly against standards of respective beams, the extension at one end of said brace depending below the lower end of the adjacent standard and the extension at the other end of said brace terminating above the lower end of the standard against which it rests, bolts passing transversely through said standards and extensions and through parts of the plow bases, a bolt passing through a part of one of said plow bases and through the depending lower portion of one of said extensions, and a bolt passing through a part of a neighboring plow base and the lower portion of the standard to which it is secured and below the lower end of the adjacent extension.
- 10 15 20 25
3. A gang plow structure comprising plow beams, said beams curved downwardly at the rear ends forming standards, bracing means between the rear portions of the

beams, said bracing means having extensions secured to the beams, and said extensions conforming to the curvature of and lying against the standards and forming supplementary parts thereof, bolts securing said beam standards and extensions together, and a plow base secured by transverse bolts to each beam standard and the brace extension lying against the same.

4. A gang plow structure comprising a plurality of beams spaced apart and provided at their rear ends with plow standard members, plow bases, braces secured between said beams and having integral extensions constituting supplementary plow-standard members lying against said standard member and means securing the supplemental standard members to the first-mentioned standard members, and transverse bolts securing both plow standard members of each beam to the adjacent plow base.

In testimony whereof, I have signed this specification in the presence of two subscribing witnesses.

RUDOLPH J. ALTGELT.
